UNITED STATES PATENT OFFICE

173,286

SLIPPER

Myer S. Silver, Brookline, Mass.

Application December 11, 1953, Serial No. 28,015

Term of patent 14 years

(Cl. D7—7)

To all whom it may concern:

Be it known that I, Myer S. Silver, a citizen of the United States, residing at Brookline, in the county of Norfolk and the Commonwealth of Massachusetts, have invented a new, original, and ornamental Design for a Slipper, of which the following is a specification, reference being had to the accompanying drawings, forming a part thereof.

In the drawings:

Fig. 1 is a plan view of the slipper;

Fig. 2 is a front elevation of the slipper;

Fig. 3 is a side elevation of the slipper; and

Fig. 4 is a rear elevation of the slipper.

I claim:

The ornamental design for a slipper, substantially as shown.
